United States Patent Office

Des. 196,810
Patented Nov. 5, 1963

196,810

HITCH PIN

Theodore F. Thompson, 409 E. 12th St., Davenport, Iowa

Filed Jan. 19, 1961, Ser. No. 63,616

Term of patent 14 years

(Cl. D54—9)

Fig. 1

Fig. 2

Fig. 3

Fig. 4

Fig. 5

Fig. 6

FIG. 1 is a perspective view of a hitch pin showing my new design;

FIG. 2 is an elevational view of the front of the hitch pin;

FIG. 3 is an elevational view of the rear thereof;

FIG. 4 is an elevational view of one side thereof, with the other side being identical thereto;

FIG. 5 is a top plan view of the hitch pin; and

FIG. 6 is a bottom plan view thereof.

I claim:

The ornamental design for a hitch pin, substantially as shown.
